SCREEDING AND FLOATING MACHINE FOR
CEMENT FLOORS

Harry H. Nichels, Jackson Heights, N. Y.

Application November 18, 1939, Serial No. 305,077

6 Claims. (Cl. 94—45)

This invention relates to screeding and floating machines for cement floors and it has for an object to make the top cement coating of floors level and of uniform compactness and a further object of the machine is to save labor in surfacing cement floors. These and other objects of the invention will be more particularly understood from the following specification and the accompanying drawing, in which:

Fig. 1 is a top plan view of the machine;
Fig. 2 is a side elevation of the machine corresponding to Fig. 1;
Fig. 3 is an enlarged transverse section on line 3—3 of Fig. 1;
Fig. 4 is an enlarged transverse section on line 4—4 of Fig. 1, and
Fig. 5 is a cross section on line 5—5 of Fig. 2, and
Fig. 6 is an end elevation of a modified form of the floating member of the machine.

Surfacing machines for concrete roadways are well known in the art, an example of which is shown in U. S. Patent 1,982,387, November 27, 1934. These are usually heavy machines adapted for use on slush concrete where the mix uses fairly large gravel or crushed stone with a water content which makes it readily flow. In the surfacing of floors for buildings and the like these machines are not suitable because their weight makes them inconvenient to handle and they are not adapted to the so-called "dry mix" concrete with the relatively small sized stone or gravel which does not flow as freely as the slush concrete and these machines do not provide for a uniform layer compacted to the same extent throughout, with a level surface, without ridges or ripples.

The present machine is adapted for floor surfacing of cement floors by applying the topping to the concrete base slab of the floor. The aggregate for this topping may comprise the portions of 1-1-1½ or 1-1-2 cement, sand and coarse aggregate which will pass through a sieve having openings between ¼ and ⅓ of an inch, mixed with a limited quantity of water so that the concrete will be stiff and uniform and easily compacted but will not flow as the ordinary slush concrete does. The compacting is necessary in order to obtain a proper bond between the base and top and to secure a dense, durable surface.

The machine for this purpose is mounted on screeds to provide a level surface for its operation and to limit the portion of floor that is being operated upon. The concrete, after grouting the base slab, and while the grout is still soft, is

spread evenly over same with a shovel or rake and sufficiently above the surface to provide for compacting the loosely placed material. The machine comprises two parallel frame members or blades which are pivotally connected to provide for a free, reciprocating motion of the forward frame member relative to the rear frame member. A motor is mounted on the rear frame member connected by an operating mechanism

10 with the front frame member to impart reciprocating motion thereto. Adjustable weights are also mounted on the rear frame member to provide the necessary pressure for maintaining the machine level in operation.

15 The aggregate accumulates against the reciprocating member as the machine moves forward. This member is provided with an inclined plane rising upwardly from the bottom edge and above this plane a horizontal row of teeth are secured

20 to the reciprocating member, so that in operation by the forward and reciprocating movements of the machine the teeth separate a predetermined section of the concrete above the level of the floor and adjacent to the inclined plane. The inclined plane compacts a portion of the concrete that has been separated and compacts and floats it into the top finish of the floor.

25 When deposited, the concrete has an open structure due to the limited quantity of water used in the mix and by forcing it through the inclined plane under the reciprocating member it is uniformly compacted which insures a proper bond between the base and the top and provides a dense, durable surface which is level and only requires finishing by troweling. This produces a smooth surface and prevents separation of the coarse from the fine material, minimizes shrinkage and keeps the coarse material at the surface to increase the resistance to wear. In the wet mix the water and the finer particles of the mix tend to come to the surface in finishing which reduces the wearing qualities of the floor.

30 An advantage of the compact, dry mix is that the men can walk on the newly finished surface for troweling, or other operations, without injuring the surface.

35 In the drawing, 11 is the rear frame member of the machine and 12 is the front frame member which is pivotally connected to the member 11 by the cross plates 13 hinged to 11 and 12 by the hinges 14, Fig. 4. A plate 15 is riveted at 16 to the rear member 11 and through the bracket 18 and roller 19 is supported by the angle 20 on the front frame member 12 which is spaced from the plate 15 as indicated at 17, Fig. 3. A

projection is provided at each end of plate 15 above the frame member 12 as indicated at 23 in Fig. 5 which engages the roller 22, mounted on the bracket 21 secured to 12. From this construction it will be noted that the vertical movement of plate 15 relative to 12 is taken up on the rollers 19 and 22.

The motor 25 is mounted on plate 15 and through belt wheel 26, belt 27 and belt wheel 28 drives shaft 29, mounted on the bearings 30 secured to plate 15. The shaft 29 is provided with an eccentric disc 31 to which the pitman 32 is connected and is pivotally connected by stud 33 to the reciprocating frame member 12. This provides a rapid, horizontal movement for the frame member 12, transverse to the screeds 53 which define the limits of the section of floor operated upon.

The machine is provided with T-handles 35 at each end which are pivotally secured to the frame members 11 and 12 and by means of which the machine may be moved by the workmen. When not in use these handles are folded down against the frame. A plate 37 is secured to the member 11 by the bolts 38 in the slotted holes at each end of the frame. Each plate is provided with an upstanding stem 39 and upon this stem a series of weights 40 are placed to load down the machine to the extent desired. A pipe rail 41 may be provided as a convenient means of moving the machine forward.

As indicated in Figs. 3 and 4 the frame members 11 and 12 are made in the form of a box girder, however, other forms may be found necessary according to the conditions under which the machine is to be used. The frame member 11 is provided with a shoe 52 made from a T-section of rolled steel which is detachably secured to 11 by bolts so that it may be replaced when worn.

A similar shoe 51 is secured to a reciprocating frame member 12. Shoe 52 is provided with an upward incline at 55 and shoe 51 has a similar upward incline at 56 in the direction of movement of the machine so that the shoe does not ruffle the surface of the finished floor. The rear of the shoes 51 and 52 are correspondingly inclined upwards at 54, Fig. 4, so as to avoid injuring the surface when the machine is moved backwards.

An inclined member 57, supported by the rail 59 is secured by the bolt 60 in front of the reciprocating member 12 as shown in Fig. 3 and this member is provided with a horizontal row of projecting teeth or fingers 61 at the top of the incline. The lower end of the inclined member 57 may be made with a hook engagement for the inclined portion 56 of the shoe 51 as indicated at 58. This separates the shoe 51 from the inclined member 57 and enables inclined members of different angles to be attached to 12.

In the construction in Fig. 6 the shoe 71 is made from sheet stock to which the U-shaped attaching member 72 is welded. This shoe is bent to form the inclined plane in front of the machine, and above the inclined plane the vertical portion 73 carries the horizontal teeth 61. The upper portion is bent horizontal at 74 and is engaged by the collar 75 on the adjusting bolt 76. This bolt is vertically adjusted in the bracket 77, secured to 12 by the nuts 78. The steel of the shoe is resilient and may be adjusted by bolt 76, up or down as indicated by the dotted lines.

In some cases, pulverized material, such as iron filings, are spread over the surface of floors be-

fore the cement sets. For this purpose a hopper is provided at 80, supported by arm 81, secured to 12 at 82, so that the reciprocating of 12 shakes the hopper 80 and delivers a stream of filings to the surface between the members 11 and 12. The member 11 in passing over the floor presses the pulverized material into the floor surface.

The weight on the reciprocating member 12 is adjusted by moving the plates 37 on the slots 10 for the bolts securing the plates to 11. The weight may be further adjusted by sliding the motor 25 on its securing bolts to plate 15, Fig. 3.

The operation of the machine will be understood from Figs. 2, 3 and 4, in which the frame members 11 and 12 are mounted on the screeds 53 and moved forward against the concrete mix b which accumulates in front of the machine and excess material may be removed by a shovel moving along the rail 59. It will be noted that the teeth 61 separates the concrete mix on the line a and in front of the incline 57 to be compacted into the floor surface c, thereby providing a concrete top surface for the floor which has a predetermined thickness and has a predetermined portion of the mix compacted into this cross section of floor, making it uniform, level, and sufficiently compact for a man to walk over it. Without the inclined plane 57 and the separating action of the teeth 61 the concrete 30 would compact in front of the member 12 and produce ridges in the surface and prevent forward movement of the machine. After the machine has been moved over the surface on the screeds and compacted, the screeds can then be 35 removed and the machine moved over the compacted surface as a finishing operation.

Having thus described my invention, I claim:

1. A machine for surfacing concrete floors with dry mix concrete comprising a first frame member moved on the floor on screeds, a second frame member, parallel with the first member and pivotally connected thereto and having a free reciprocating motion with relation to the first member, a motor secured to the first frame member and movably supported by the second frame member, means connecting said motor with the second member to reciprocate the second member, shoes provided for said members to slide on the screeds, an inclined member projecting upwardly and forwardly from the shoe on the reciprocating member, a parallel row of teeth projecting from said inclined member above the floor level into the dry mix concrete to separate the portion of the mix above the teeth from a predetermined portion below the teeth to enable the predetermined mix in front of the inclined portion to pass under and be compacted by the shoe of the reciprocating member as the machine is moved forward on the floor against the concrete mix.

2. A machine for surfacing concrete floors with dry mix concrete comprising a frame member moved on the floor on screeds, a second frame member parallel with the first member and pivotally connected thereto and having a free reciprocating motion with relation to the first member, a motor secured to the first member and movably supported by the second frame member, means connecting said motor with the second member to reciprocate the second member, shoes provided for said members to slide on the screeds having the edge inclined upwardly, an inclined member engaging the upwardly inclined edge of the shoe secured to the reciprocating member, a parallel row of teeth projecting

above the floor level from said inclined member into the concrete mix in front of the machine to separate the portion of the mix above the teeth from a predetermined portion below the teeth to enable the mix in front of the inclined portion to pass under and be compacted by the shoe of the reciprocating member as the machine is moved forward on the floor against the concrete mix.

3. A machine for surfacing concrete floors with a dry concrete mix comprising a spreading blade operated against the mix as it is moved forward, means for reciprocating said blade, the base of said blade having a front member upwardly and forwardly inclined with a horizontal row of teeth therein spaced above the floor level engaging the loose mix in front of the spreader blade to separate a definite portion of the mix and force it under the spreading blade as the blade moves forward.

4. A machine for surfacing concrete floors with a dry concrete mix comprising a spreading blade operated against the mix while it is moved forward, means for reciprocating said blade and means on the blade spaced above the floor level for separating a definite portion of the loose mix in front of the spreader blade and compacting it into the floor to produce a uniform density in the finished floor.

5. A machine for surfacing concrete floors, comprising a frame member moved on the floor, a

second frame member parallel with and spaced from the first frame member and pivotally connected thereto and having a free reciprocating motion with relation to the first member, a motor secured to the first frame member and movably supported by the second frame member, means connecting said motor with the second member to reciprocate the second member, a shoe for each of said members engaging the surface of the floor and a hopper with pulverized material located between said members and rocked by said reciprocating member to spread the material on the surface as it is being finished.

6. A machine for surfacing concrete floors comprising a frame member moved on the floor on screeds, a second frame member parallel with the first member and pivotally connected thereto and having a free reciprocating motion with relation to the first member, a motor secured to the first frame member and movably supported by the second frame member, means connecting said motor with the second member to reciprocate the second member, a shoe for said second member sliding on the screeds, said shoe being made from sheet stock and secured to the bottom edge of the frame member, said stock being resilient and inclined upwards from the bottom and forward of the machine and having an extension, and an adjusting bolt engaging said extension and a bracket secured to the frame member supporting said bolt.

HARRY H. NICHOLS.
